US00D396620S

United States Patent [19]

Sung

[11] Patent Number: Des. 396,620
 [45] Date of Patent: **Aug. 4, 1998

[54] IMPACT WRENCH

[75] Inventor: Eric Sung, Taichung County, Taiwan

[73] Assignee: K.K.U. Limited, Tokyo, Japan

[**] Term: 14 Years

[21] Appl. No.: 53,004

[22] Filed: Apr. 30, 1996

Related U.S. Application Data

[63] Continuation-in-part of Ser. No. 43,846, Sep. 11, 1995, Pat. No. Des. 378,891, and Ser. No. 43,731, Sep. 11, 1995, Pat. No. Des. 377,894.
